CLAIM

The ornamental design for a stand for wrist-worn electronic device, as shown and described.

DESCRIPTION

FIG. 1 is a front perspective view of a stand, having a supporting member and an electronic device holder, for wrist-worn electronic device showing my new design; FIG. 2 is a rear perspective view thereof; FIG. 3 is a front elevational view thereof; FIG. 4 is a rear elevational view thereof; FIG. 5 is a left side elevational view thereof; and FIG. 6 is a right side elevational view thereof; FIG. 7 is a top plan view thereof; FIG. 8 is a bottom plan view thereof; FIG. 9 is a front perspective view of the supporting member; FIG. 10 is a rear perspective view of the supporting member; FIG. 11 is a front perspective view of the electronic device holder; FIG. 12 is a rear perspective view of the electronic device holder; FIG. 13 is a front perspective view of the stand for wrist-worn electronic device in which the supporting member and the electronic device holder are shown separated for clarity of disclosure; and, FIG. 14 is a rear perspective view of the stand for wrist-worn electronic device in which the supporting member and the electronic device holder are shown separated for clarity of disclosure. The broken lines illustrate portions of the stand for wrist-worn electronic device and form no part of the claimed design.
